FEEDING DEVICE FOR ENVELOPE FOLDING
MACHINES OR THE LIKERobert A. Nelson, Cleveland, Ohio, assignor to
The Standard Envelope Manufacturing Company, Cleveland, Ohio, a corporation of Ohio

Application April 28, 1931, Serial No. 533,483

3 Claims. (Cl. 271—36)

The invention refers to feeding devices for envelope-folding machines or the like and has as its general aim the provision of a new and improved feeding device which is simple in construction, efficient in operation, and which is capable of being quickly and accurately adjusted to feed blanks of different sizes or to readjust the device to eliminate such inaccuracies as may occur from operation, as by wearing of the parts.

10 It is an object of the invention to provide a new and improved means for feeding envelope-blanks one after another from a stack of blanks presented to the feeding mechanism from a magazine, which device embodies a means for withdrawing blanks from the magazine, and means adjustable in a novel manner for preventing the withdrawal of more than a single blank.

More specifically stated, an object of the invention resides in the provision of a device of this 20 character in which a rotatable member is adapted to withdraw blanks from the magazine, and a blank holding means is operative to prevent the withdrawal of more than a single blank from the magazine, said blank-holding means having an 25 adjustable movement toward and away from said rotatable member in such a direction that wear of said holding means is evenly and equally distributed throughout the entire area of the surface of said means which is in contact with the moving blank.

In conjunction with the foregoing, another object of the invention is to provide means for moving the blank-holding means toward and away from the rotatable member with exceeding accuracy.

Another object of the invention resides in the provision of a rotatable member for withdrawing blanks from the magazine, which member carries peripherally projecting blank-engaging devices 40 of an improved form capable of being easily adjusted from an out-of-the-way point within the periphery of said member.

Another object is to provide, in a feeding device embodying a pair of opposed feeding rolls, a novel means for yieldingly urging said rolls toward each other.

Stated more specifically, an object of the invention resides in the provision of an improved feeding device having opposed upper and lower feeding rolls, between which a blank passes to other operative mechanisms, and means for supporting said lower roll in resiliently urged and yielding contact with said upper roll.

55 Other objects and advantages will become ap-

parent in the following description and from the accompanying drawings, in which:

Figure 1 is a fragmentary plan view of a machine embodying the features of the invention.

Fig. 2 is a longitudinal vertical section through the feeding rolls of the machine taken substantially along the line 2—2 of Fig. 1.

Fig. 3 is a similar section showing the feeding rolls in elevation and is taken as indicated by the line 3—3 of Fig. 1.

Fig. 4 is a fragmentary elevation of the machine looking in the direction indicated by the line 4—4 of Fig. 1.

Fig. 5 is a detail view showing the blank holding device in rear elevation as indicated by the line 5—5 of Fig. 3.

Fig. 6 is a substantially vertical section through the blank-holding device taken on the line 6—6 of Fig. 3.

Fig. 7 is a fragmentary vertical section on an enlarged scale through the feeding rolls showing the operation of the device.

Fig. 8 is an elevational view of the upper feeding roll.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The present invention is illustrated and will be described as being applied to an envelope-folding machine in which envelope-blanks are successively fed from a stack of blanks in a magazine to a conveyer which carries the blanks into or through the folding mechanism of the machine. While the articles which are operated upon by the present device have been, and will hereinafter be termed envelope-blanks, it will be understood that this term is generically indicative of blanks other than the properly-shaped blanks from which envelopes are fashioned.

Referring more particularly to the drawings, a magazine for presenting envelope-blanks to the feeding device is illustrated in Figs. 1, 2 and 4 as comprising a transversely extending flat base member 20 having parallel, vertically extending, and laterally adjustable side walls 21 thereon. The discharge side of the magazine, or in other words that side which is positioned adjacent the feeding device, is supported by opposed brackets 105 110

22 rigid with the bed 23 of the machine. The other side of the magazine is supported in any suitable manner which permits the slope of the bottom thereof to be adjusted as, in this instance, 5 by means of a rod 24 which extends between the magazine and an adjustable fastening device 25 on a stationary part of the machine. The base 20, as may be seen in Fig. 1, preferably does not extend as far toward the feeding device as do the 10 side walls 21, the gap thus formed being spanned in any suitable manner, as by a pair of plates 20^a supported on the base 20 between the walls 21 in centrally overlapping relation to each other to allow of lateral adjustment as to width. The 15 plates 20^a are preferably somewhat arcuate at their free ends (see 20^b, Fig. 2) to insure a proper delivery of the blanks to the feeding device.

The feeding device is interposed between the magazine and a blank-conveying means herein 20 shown in the form of endless chains 26 (Fig. 1). Broadly, the feeding device embodies a feeding roll having means thereon for engaging the uppermost or top blank presented thereto by the magazine. Said roll acts in conjunction with a blank-holding or retaining means which is positioned 25 adjacent the periphery of said roll and is adjustable to provide a clearance between said means and said roll only sufficient to allow a single blank to pass therebetween. A second feed roll, opposed 30 to and running in contact with the first feed roll, forms, with said first feed roll, a means for engaging the blank after it has passed between the first feed roll and the blank-holding means and for feeding said blank into a position where it 35 may be engaged by the conveyer chains 26. While the present device is illustrated as being adapted to extract the top blank from a stack of blanks in a magazine, it will be evident to anyone skilled in the art that, with minor modifications and 40 changes, the device may be adapted to feed from other parts of the stack.

Referring to Figs. 1 and 4, the upright brackets 22 on the bed 23 are provided with aligned bearings 27 to receive a shaft 28 which extends 45 transversely of the bed adjacent the discharge end of the magazine. The shaft 28 carries a disk-shaped feeding roll 29 which is rigid with, yet is adjustably secured to, the shaft by such means as screws 30 (Fig. 3) extending through a hub 31 on the disk into engagement with the shaft. The hub 31 is preferably formed by cutting away intermediate portions of the disk. The relationship of the disk and magazine is such that a peripheral portion of the disk extends a short distance into the magazine and is located substantially intermediate the magazine side walls 21.

The disk carries a plurality of closely spaced peripherally projecting blank-engaging members 32 (Figs. 2, 7 and 8), three pairs of such members being shown in the present instance. The members 32 are preferably in the nature of plugs formed of rubber or other suitable friction material and are mounted in bores or recesses 33 which extend radially from the peripheral surface of the disk. Means is provided for adjusting the plugs radially with respect to the disk as they become worn, which adjustment is preferably effected from an out-of-the-way position within the periphery of the disk. To this end, 55 each of the plugs 32 is secured to a plate 34 which, in turn, is rigid with a screw-threaded shank 35.

The disk 29, intermediate the bores 33 and the center of the disk, is transversely apertured as at 36, and bores 37, extending axially of the recesses 33, connect said recesses with the aperture

36. The bores 37 are internally screw-threaded to engage the threads on the shanks 35 whereby to mount the plugs in the recesses 33, and the free ends of the shanks 35 are squared, as at 38, to facilitate engagement thereof by a suitable tool for adjusting the position of the plugs 32. It will be evident, therefore, that the plugs are rigidly mounted in the disk and that the position thereof may be readily adjusted from a position within the periphery of the disk. In operation, as the disk 29 is rotated, the plugs 32 are recurrently brought into engagement with the top one of the blanks in the magazine to withdraw said blank therefrom. 80

The means which cooperates with the feed roll 29 to prevent movement of all except the top blank out of the magazine, as the feed roll rotates, is, in this instance, disposed beneath the magazine and adjacent to the feed roll. Thus, the side brackets 22 support a stationary rod 39 positioned immediately below the discharge side of the magazine. Preferably, the rod 39 is capable of adjustment toward and away from the magazine, this end being herein accomplished by means of elongated slots 40 (Fig. 4) in the brackets and bolts 41 carried by the shaft 29 and engaging said slots. This manner of mounting the shaft also permits the shaft to be rotatably adjusted. 85

The shaft carries a block 42 (Figs. 2 and 3) 90 having a transverse aperture 43 through which the shaft extends and a longitudinally extending key-way 44 in the shaft is arranged to be engaged by a set screw 45 carried by the block adjustably to affix the block on the shaft. The upper surface of the block (see Figs. 2 and 6) has a pair of spaced guides 46 which extend in a direction at right angles to the axis of the transverse apertures 43 and shaft 39. These guides 46 cooperate with a pair of complementary guides 47 formed 95 on the lower surface of a slide 48, which slide, in this instance, is generally triangular in shape. 100

The upper surface of the slide 48, or that surface which is opposite the surface on which the guides 47 are positioned, is provided with a longitudinal recess 49 arranged to receive an elongated block 50 which constitutes the blank-holding member. The arrangement and disposition of parts, as may be clearly seen in Fig. 2, is such that when the slide 48 is mounted on the block 105 42, one end of the block 50 is juxtaposed with respect to the periphery of the feed roll 29. This end of the block is formed substantially on the radius of the feed roll to provide an arcuately concaved recess which conforms to the curvature 110 of the periphery of the feed roll. In operation, the arcuately recessed face on the block 50 is positioned adjacent the periphery of the feed roll, with only sufficient clearance therebetween to permit a single blank to pass. Thus, the block 115 50 retains all except the upper blank in the magazine. 120

Obviously, in use, the block will wear away somewhat rapidly and in time, unless adjusted, a clearance sufficient to allow more than one blank 125 to pass will result. Heretofore, the adjustment of the block has been effected by pivotally mounting the block so that the upper transverse edge of the recess or, as it may be termed, the heel could be adjustably swung toward or away from 130 the feed roll. This manner of adjusting the clearance has been found to be disadvantageous due to the fact that wear of the block was unequally distributed throughout the recess. In time, this produced a recess which did not conform to the 135 140

145 150

curvature of the feed roll, and in which the clearance at the tip or toe of the recess was much greater than the theoretically correct clearance. This disadvantage is overcome in the present 5 development by the previously described mounting of the block. That is to say, the triangular shape of the slide 48 allows the block 50 to be supported substantially in the line of feed and at a proper feeding angle with respect to the 10 feed roll, while the direction of movement of the block is at an acute angle to the blank engaged face of the block and, hence, to the line of feed as well. Thus, it will be seen that the block 50 has a direction of movement relative to the 15 feed roll which adjusts the entire recess therein radially of the roll. This direction of movement of the block, as is clearly apparent in Figs. 2 and 3, extends across the feed roll at some point intermediate the axis of said roll and the 20 periphery thereof. As a result, once the device has been set by adjustment of the rod 39 vertically and rotatably to properly locate the direction of movement of the block relative to the roll, any adjustment for wear maintains the 25 desired equidistant relationship of the opposed faces.

Means is provided for moving the block 50 in proper direction, which means is adapted to permit of an exceedingly fine adjustment of the 30 block relative to the feed roll, as well as to rigidly affix the parts in any position of adjustment. To this end, the block 42 has a transverse slot 51 of rectangular cross-section (see Figs. 2 and 35 6) disposed at right angles to the axis of the aperture 43 and intermediate the guides 47 on the block. The slot 51 receives an elongated headed bolt 52 which is screw-threaded into an appropriate socket in the slide 48. The head of the bolt is arranged to bear against a washer 53, interposed between said head and the adjacent side of the block 42, whereby the slide 48 40 may be rigidly secured to the block 42. The rear side of the slide 48 carries a plate 54 (Figs. 2 and 5) which has an end projecting beyond the slide into overlying relation with respect to the 45 block 42. This projecting end of the plate carries a screw 55 arranged for rotative, but non-axial movement relative to the plate. The end of the screw 55 engages a tapped bore, or its equivalent, in the block 42.

50 It will be evident that rotation of the screw 55, by means of a suitable finger piece 56, will produce a guided movement of the block 50 toward or away from the feed roll 29 when movement of the slide 48 relative to the block 42 is permitted by loosening the bolt 52. Consequently, an exceedingly accurate adjustment of the clearance between the block 50 and the periphery of the feed roll to permit only a single blank to pass therebetween may be attained. When this 55 adjustment has been made, the bolt 52 is tightened rigidly to maintain the adjustment until wear of the block 50 requires a readjustment of the clearance.

The second feed roll, indicated at 57 (Figs. 2 and 3), is supported by a shaft 58, an antifriction element 59 being preferably interposed to allow the second feed roll 57 to rotate freely relative thereto. Preferably, the antifriction element is keyed, as at 58^a (Fig. 3) to the shaft 58 60 for axial sliding movement. Side plates 57^a on the feed roll 57 maintain assembly of the parts. The shaft 58 extends transversely of the machine immediately below and paralleling the upper feed roll shaft 28 and, in the present instance, 65 is supported for vertical movement to carry the

second feed roll 57 into and out of engagement with the upper feed roll 29. One form of means for so supporting the shaft 58 is illustrated in Figs. 1 and 4 as comprising bell-crank levers 60 rigidly secured to opposite ends of a transversely extending rock shaft 61 as by means of the pins 61^a. One arm 60^a of each lever extends horizontally and said arms are provided with suitable bearings to receive and support the opposite ends of the shaft 58.

85 A spring 62 extends between each of the other arms 60^b of the levers 60 (which arms, in this instance, extend downwardly from the pivotal point of the lever), and a stationary part of the machine. The springs exert a force on the bell-crank lever which normally tends to swing the shaft 58 upwardly and maintain the lower feed roll 57 in contact with the upper feed roll 29. If desired, means may be provided for limiting the movement of the bell-crank lever under the spring tension, such as a set screw 63, adjustably carried in a stud 64 for engagement with the arms 60^b of the bell-crank levers. The shafts 28, 58 and 61 are arranged in parallelism and this relationship is maintained in operation, by the 90 rigid connection between the bell-crank levers 60 and the rock shaft 61. Thus an even engagement of the feed rolls is insured.

95 The upper feed roll 29 is preferably driven in the following manner: A beveled gear 65 (Fig. 1) 105 mounted on a stub shaft 66 (Figs. 1 and 4) is arranged to be driven from any suitable source of power (not shown). The stub shaft 66 carries a gear 67 which meshes with a complementary gear 68 arranged, in this embodiment, for rotation about the pivot 61 of the bell-crank lever 60 110 as an axis. The gear 68 meshes with a third gear 69 (Fig. 4) which, in turn, meshes with a large gear 70 rigidly affixed to the upper feed roll shaft 28.

115 The gear 69 is rigid with the shaft 58 to drive said shaft. Since the swinging movement of the shaft 58 is about the axis of the gear 68 as a center, the gears 68 and 69 are constantly in mesh. However, this swinging movement is of such 120 limited extent that the gears 69 and 70, while movable toward and away from each other, never become disengaged. As has been stated, the shaft 58 is preferably driven. Consequently, and although the feed roll 57 may rotate relatively 125 to the shaft (because of the antifriction element 59), the lower feed roll is driven yet may rotate independently and at variable speeds according to the machine operation.

130 It will be apparent from the foregoing that a novel device of this character has been provided which may be adjusted simply and quickly for blanks of various sizes and shapes. Thus, to set up the device, the side walls of the magazine are adjusted to proper width and the magazine as a 135 whole arranged at a proper feeding angle to the feed rolls. The upper feed roll is rigidly secured to the shaft 28 at approximately the center of the magazine. The blank-holding means is adjusted along the rod 39 to correspond to the position of the upper feed roll and the correct angular disposition of the means is attained by adjustment of the rod 39. Preferably, movement of the blank-holding means axially of the rod 39 is utilized to properly position the lower feed roll in 140 opposition to the upper feed roll. Thus, the block 42 on the rod 39 has side plates 71 (Figs. 2, 3 and 6) which extend therefrom to straddle the lower feed roll 57 and hold the parts in a definite 145 aligned relationship.

Clearance between the block 50 and the periphery of the upper feed roll is accurately adjusted to allow only a single blank to pass therebetween and the device is ready for operation. It is, of course, presumed that the feeding plugs 32 are so adjusted that they project from the periphery of the feed roll to engage the upper blank presented thereto by the magazine. By the present device, adjustments required to compensate for wear 10 may be made without difficulty. The plugs 32 are conveniently adjustable from within the periphery of the upper feed roll. The block 50, when the screw 55 is turned, is moved accurately in a proper direction toward the upper feed roll 15 to space the entire surface of the recess in the block equidistantly from the roll.

The operation in general is so obvious as to require no additional explanation. It should be noted, however, that the mounting of the lower feed roll for movement toward and away from the upper feed roll allows the position of the upper roll to be definitely and rigidly maintained yet insures that the device will operate efficiently upon blanks of different thicknesses. Moreover, 20 the possibility of blanks becoming wedged or "jammed" between the feed rolls is eliminated.

I claim as my invention:

1. In a device of the character described, the combination of a magazine, a first feed roll adapted to engage and withdraw blanks successively from said magazine, means adjustable transversely of said magazine to cooperate with said first feed roll to prevent withdrawal of more than one blank at a time; a second feed roll adapted 30 to run in contact with said first feed roll, a supporting shaft on which said second roll is mounted for axially sliding movement, and means con-

nected said second feed roll and said transversely adjustable means for transverse movement together.

2. A feed roll for a device of the character described comprising, in combination, a disk-like member having a series of recesses extending inwardly of said member from the periphery thereof, a plug of blank-engaging material in each recess, and means for independently adjusting the positions of said plugs, said means being operable from within the periphery of said member, said member being cut away to provide access to said means.

3. A feeding device for envelope-blanks or the like comprising, in combination, a blank-presenting magazine, a feed roll arranged to engage and withdraw blanks therefrom, and means arranged to engage said blanks and having a spaced relation to said roll to prevent more than a single blank from being withdrawn at any one time, said means comprising a stationary block disposed below and at one side of said feed roll and having upwardly facing guide means thereon disposed in a plane which slopes upwardly toward the adjacent part of said roll, a triangularly shaped block mounted on said guide means with a surface thereof extending generally in the direction of the line of feed, a blank engaging member mounted on said surface and having a concave face opposing said roll, and means for adjusting said block along said guide means, said parts having a relationship wherein movement of said block adjusts said concave face toward or away from said roll while maintaining the opposing faces concentric.
